OIL REFINING

Application filed August 12, 1927. Serial No. 212,376.

This invention relates to the refining of oils by cracking processes. Such processes as heretofore practised have always involved the release of considerable quantities of carbon and fixed gases. The deposit of a relatively large volume of carbon has in fact been considered an essential feature of the cracking reaction. This carbon while useful as it is, in the form of coke, for fuel purposes, nevertheless is a detriment in the cracking operation, limiting the periods of action and imposing losses in the shut-down periods for cleaning-out, etc.

Special objects of the present invention are to reduce the formation of coke and fixed gases, with their attendant wastes and losses, to produce a marketable residuum and to improve oil refining operations generally.

The foregoing and other desirable objects are attained by certain novel features of process, construction and operation as set forth in the following specification, illustrated in the accompanying drawings and broadly covered in the appended claims.

In the drawings, Figure 1 is a broken part sectional and more or less diagrammatic representation of a fundamental form of apparatus suitable for practising the invention.

Figure 2 is a similar view of apparatus illustrating a further development of the invention.

Figure 3 is a broken detail view illustrating a modified form of pressure reducing means and control.

The invention involves, as one of its main features, the discovery that the deposit of considerable quantities of carbon is not a necessary accompaniment to the production of lower boiling point oils in cracking processes and that the lighter products taken off "overhead" can in effect be balanced by the heavier products retained in the residuum.

In the practise of the invention, the cracking is effected as one phase of the operation and separation as another phase of the operation, precipitation of carbon being prevented during the cracking by circulating the liquid at sufficient velocity to overcome the precipitation tendency and formation of carbon being prevented in the separating stage by

dropping the pressure and removing the residuum from the separating zone as fast as the vapor is released. To gain the time required for the cracking operation, the cracking conduit is lengthened sufficiently to compensate for the increased rate of travel. Thus, while the tube still indicated at 3 is shown as of typical design, it differs from the standard constructions in that the overall length of the tubes 4 is sufficiently greater than in ordinary stills to give the requisite cracking time, with the increased velocity of flow.

The separating chamber shown at 5 is of a size sufficient to facilitate the release of the vapors, but because of the fact that no accumulation is permitted therein, may be much smaller in size than the so-called "reaction" chambers employed in pressure-system cracking.

The transfer line from the tube still to the separating chamber is designated 6.

In the primary or fundamental embodiment of the invention, illustrated in Figure 1, the pressure is reduced at a point in between the end coil of the still and the separating chamber. In the present showing, the reduction is effected by a reducing valve indicated at 7 in the transfer line, relatively close to the still so that the cracked product flows along and enters into the top of the separator under reduced pressure. The reduction in pressure, for example, may be from approximately 200 lbs. at the still to about 30 lbs. in the separator.

Some pressure, such as the latter, has been found desirable to enforce the constant discharge of the residuum from the separator. The residuum discharge line is indicated at 8, extending from the bottom of the separator and the vapor line is shown at 9 extending from the top of the separator to the dephlegmator 10. The discharge or withdrawal of the residuum is regulated or controlled so that it is removed constantly and practically as fast as the vapors are released. The reduction to below the cracking pressure and the constant removal of the residuum from the separating zone have the effects of preventing carbon deposit in the separator and

of keeping the carbon in suspension. The residuum, therefore, is a high carbon content fuel oil which is a commercially saleable product as such.

5 The pressure distillate is shown as passing off from the top of the dephlegmator through a vapor line 11 to a suitable condenser 12. A gas separator is indicated at 13 for removing the fixed or non-condensable gases, this separator having a discharge line 14 for the gas and a line 15 leading to the gasoline storage.

15 The raw stock is shown as supplied by a feed line 16 to a heat exchanging coil 17 in the top of the dephlegmator, the stock passing from said heating coil into the dephlegmator at 18 and the heat exchange being controlled by a valved by-pass 19 about said coil.

20 The reflux leg of the dephlegmator is shown connected at 20 with a hot oil pump 21 connected at 22 with the inlet coil of the still.

25 The form of apparatus shown in Figure 2 differs from that just described principally in that a second separating chamber is provided, as indicated at 23, and in that the pressure on the oil is reduced at a point in between these two chambers. The reducing valve in this case is shown at 24 in the residuum line 25.

35 The general principle of operation is the same in that the velocity of the oil is stepped up to overcome the tendency to deposit carbon in the tubes of the still, the tubes are of sufficiently greater length than ordinary to compensate for such increased velocity and provide the necessary cracking time and the oil is continuously removed from the separating chamber to prevent or reduce deposit of carbon therein. The second separating chamber, at the reduced pressure, acts as a "flash chamber", the overhead passing off through a vapor line 26 and the residuum passing off as a commercial fuel oil through 40 the residuum line 27.

45 The second view illustrates also the possibilities of positively drawing off from the second separating chamber either the overhead or the residual oil, or both, for instance in cases where a quite low pressure or even absence of pressure is permitted in the separating chamber. Thus the overhead is shown as taken off by an injector 28 which is supplied with raw stock through a feed line 29 and the residual oil is taken off by a pump 30 which is shown discharging through a line 31 to residuum cooler 32 and storage.

55 Another additional feature illustrated in Figure 2 is the employment of a heat exchanging mixing column 33 into which the injector discharges the raw stock and overhead from the second separator. The pressure distillate goes off from this mixer through a vapor line 34 to a suitable condenser 35, discharging into the receiver and the

oil is taken off at the bottom by connection 36 and passed by the pump 37 through the feed line 38 to the top of the dephlegmator, which last connection corresponds in its effect with the feed line 16 in Figure 1.

70 With the apparatus constructed as disclosed and the process carried out as described, the carbon is largely retained in the residual oil, the residual oil is a commercially saleable fuel oil, the proportion of fixed gases 75 is materially reduced and while in the commercial practise of the invention thus far, some carbon is precipitated in the separating chamber or chambers, this deposit is so much less that the system can be kept in operation without shut-down for much longer periods than has heretofore been possible under approved continuous pressure systems.

75 Each embodiment of the invention illustrated has certain advantages. In the second form, it will be observed that a part of the vapor is removed from the system at the top of the mixer or gas oil condenser 33 so that a portion of the gasoline is taken out without having to pass it through the dephlegmator tower. By preventing accumulation of oil in the first separating chamber and drawing it off immediately to the second or low pressure chamber, where pressure and temperature are both reduced, there is no subjection of the oil 90 to the higher cracking conditions which have heretofore obtained in pressure systems and as a consequence, deposit of carbon is almost entirely eliminated. The removal of the heavy oil from the high pressure zone practically as soon as it is formed, stops the action which otherwise would convert this heavy oil into coke and fixed gas and keeps the coke suspended in the form of fuel oil. The mixing of the gas oil taken off from the second separator with the raw oil introduced in the gas oil condenser materially increases the reflux ratio through the furnace. Because of the greatly lengthened operating cycles, the wear 100 and tear on the apparatus is very materially reduced and operating expenses are cut down. The action also is smoother and more nearly automatic and in actual operation a higher percentage of gasoline in the pressure distillate as compared with existing pressure systems, has been obtained.

105 The fuel oil is a usable product for industrial purposes and so can be taken out of the system in larger quantities than heretofore, at a profit, considering that the carbon is saved and made use of by keeping it in the liquid state in this oil. The apparatus as a whole is relatively simple, all the heat being applied at but one point; that is, at the pressure still, which except for the lengthening of the tubes and clearance provided for increased oil velocity, may be of generally standard construction.

110 It will be obvious to those skilled in this art 115 that certain changes and modifications may 120

be made without departure from the true spirit and broad scope of the invention. Thus for example, the pressure reducing valves may be of the automatic self-regulating type as shown at 7 and 24 in Figures 1 and 2 or as an alternative, manually controlled means may be used for the purpose, such as illustrated in Figure 3. In this last mentioned view, the transfer line 6 is shown as branched at 39 and as having in these branches the pressure reducing contracted throats 40, 41, controlled respectively by valves 42—42, 43—43. These throats are indicated as of different sizes and the valves enable them to be used interchangeably, or both at the same time, and in the latter event, one more or less than the other. These reducing throats are designed so that stoppage will not occur therein, but the presence of the two branches is an advantageous service feature in that there is always a reserve branch to be used in case of any choking in the other.

What is claimed is:

1. A process of cracking oil which comprises heating hydrocarbon oil to cracking temperature under pressure in a long cracking coil to crack the oil extensively while flowing the oil through said coil at a sufficiently rapid rate to carry out the carbon formed in suspension, passing the cracked oil and suspended carbon into the upper portion of an enlarged zone to effect the separation of the light cracked products by distillation, removing the separated vapors, separately withdrawing the liquid from said enlarged zone at a rate adequate to prevent accumulation of substantially any oil therein, stripping the lighter fractions of the discharged residual oil by suddenly expanding it at low pressure into a flash chamber where copious vaporization by its contained heat takes place, and withdrawing a high grade fuel oil from the bottom of said flash chamber.

2. A process of cracking oil which comprises charging a stream of hydrocarbon oil once through a cracking coil maintained under cracking temperature and pressure at sufficient velocity to carry the carbon resulting from cracking therein out of the coil without deposition, curtailing further cracking of liquid constituents and separating the light cracked products by delivering the carbon-containing oil into an enlarged chamber where no substantial accumulation of liquid oil is permitted, the residual carbon-containing oil being rapidly discharged therefrom and from the cracking system to prevent accumulation of liquid in said chamber, removing the vapors from said chamber, separating out the heavier constituents thereof by partial condensation, expanding the discharged residual oil at low pressure into a flash chamber to vaporize the lighter constituents by the contained heat of the oil, withdrawing the heavier bottoms from the flash chamber

as fuel oil, mixing fresh charging stock with the overhead vapors from said flash chamber, removing the lighter constituents of the mixture as vapors, and introducing the preheated mixture and the hot condensate from said initial partial condensation into the coil to be cracked therein.

3. A process of cracking oil which comprises heating to cracking temperature hydrocarbon oil under pressure and in a rapidly flowing stream in a highly heated cracking coil, delivering the cracked oil into an enlarged chamber where vaporization takes place, passing the vapors into a dephlegmator to condense out the heavier constituents as a condensate, discharging the heavy carbon-laden residual oil from said chamber at a sufficiently rapid rate to substantially prevent accumulation of liquid in said chamber while delivering said residual oil into a flash chamber under low pressure where the contained heat of the oil effects copious vaporization thereof, discharging the heavy unvaporized liquid from the flash chamber, partially condensing the overhead vapors from said flash chamber by mixture with a stream of charging oil while distilling off the lighter constituents of the charge oil, removing the combined light vapors from said mixture, charging the unvaporized portions of said mixture in preheated condition into said dephlegmator and introducing the heavier portions of said preheated mixture and said condensate from said dephlegmator to the coil to be cracked therein.

4. A process of cracking oil which comprises cracking hydrocarbon oil under heat and pressure, distilling off the light cracked products as vapor, expanding the unvaporized residual oil with carbon in suspension into a flash chamber at substantially atmospheric pressure where the lighter constituents are distilled off by the contained heat thereof, discharging the heavier unvaporized carbon-containing oil as fuel oil from the bottom of said flash chamber, assisting the removal of vapors from the flash chamber by injector action from a stream of charging oil injected into and mixing with the overhead vapors from the flash chamber, removing the lighter constituents of the mixture as vapors and delivering the preheated heavier liquid constituents under pressure to the cracking zone.

5. A process of cracking oil which comprises heating to cracking temperature a stream of hydrocarbon charging oil, mixed only with clean condensate produced in the process, to the desired extent as it flows under pressure through a cracking coil with sufficient rapidity to prevent deposition of carbon therein, delivering the efflux from said coil without material pressure reduction into an enlarged unheated chamber where vaporization takes place and accumulation

- of liquid is substantially prevented by the rapid and continuous discharge of residual oil therefrom at such a rate as to prevent said residual oil from remaining in the chamber for a sufficient length of time to permit the formation of carbon therein, reducing the pressure materially on the discharged residual oil and distilling it under its contained heat to leave a liquid fuel oil of small carbon content, subjecting the vapors evolved in the enlarged vaporizing chamber to reflux condensation, and returning the condensate unmixed with residual oil to the cracking coil for further cracking.
- 15 6. A process of cracking hydrocarbon oil which comprises heating the oil to cracking temperature as it flows under superatmospheric pressure through a heated coil, passing the oil thence into an enlarged reaction chamber maintained under superatmospheric pressure wherein separation of vapors and liquid occurs, removing the separated vapors, withdrawing liquid from said enlarged chamber at a rate adequate to prevent accumulation of liquid therein and expanding the liquid thus withdrawn directly into a flash chamber and effecting distillation by means of the contained heat of said liquid under reduced pressure.
- 20 7. A process of cracking hydrocarbon oil which comprises subjecting the oil to cracking temperature under superatmospheric pressure as it flows through a heated coil, passing the oil thence into an enlarged reaction chamber wherein without any material reduction in pressure separation of vapors and liquid occurs, removing the separated vapors, withdrawing liquid from said enlarged chamber at a rate adequate to prevent accumulation of liquid therein and expanding the liquid thus withdrawn directly into a flash chamber and effecting distillation by means of the contained heat of said liquid under reduced pressure.
- 25 8. A process of cracking hydrocarbon oil wherein the oil is raised to a cracking temperature as it flows through a heated coil, is passed thence into an enlarged reaction chamber from which vapors and liquid are
- 30 9. A process of cracking hydrocarbon oil which comprises heating the oil to cracking temperature as it flows under superatmospheric pressure through a heated coil intro-

ducing the heated oil into the top of an enlarged reaction chamber maintained under superatmospheric pressure wherein separation of vapors and liquid occurs, removing the separated vapors, withdrawing the precipitated liquid from the bottom of said enlarged chamber at a point remote from that of the introduction of the oil to the chamber and at a rate adequate to prevent accumulation of liquid therein and expanding the liquid thus withdrawn directly into a flash chamber and effecting distillation by means of the contained heat of said liquid under reduced pressure.

In testimony whereof, I have signed my name to this specification this 16th day of July, 1927.
